SAFETY DEVICE FOR PRESSING MACHINES

Albert Matthews, Cincinnati, Ohio, assignor to
American Laundry Machinery Company, Nor-
wood, Cincinnati, Ohio, a corporation of Ohio

Application September 11, 1933, Serial No. 688,992

6 Claims. (Cl. 38—40)

This invention relates to a safety device for pressing machines, and more particularly to pressing machines of the scissors type having balance springs for normally retaining the pressing head in open position and the provision in such a machine of means for preventing the closing of the pressing members upon failure of the balance springs.

An object of the invention is to provide a safety latch arranged to automatically lock the pressing head to the frame of the pressing machine upon failure of the head balance springs.

Another object of the invention is to provide a safety means operable automatically to hold the pressing head of a power-operated press in open position upon failure of the head balance springs, said safety latch being arranged to prevent operation of the power means until the damaged springs are repaired.

A further object of the invention is to provide a safety latch as above described, together with means for moving the latch to inoperative position automatically upon application of power to the power means.

Further objects and advantages of my improved safety device will be apparent from the accompanying description together with the drawing, and the essential features of which will be summarized in the claims.

In the drawing, Fig. 1 is a side elevation, partly in section, of a pressing machine embodying my invention; Fig. 2 is a partial side elevation showing the latching mechanism of Fig. 1 in latched position; Fig. 3 is a partial sectional view showing the latching mechanism in inoperative position; Fig. 4 is a section along the line 4—4 of Fig. 1; while Fig. 5 is a partial sectional view of valve mechanism for the power cylinder of Fig. 1.

I have illustrated my invention as applied to a press of the scissors type having the usual head lever provided with toggles, which in their straightened position move the head to closed position, and a balance or retriever spring for returning the head to open position. Upon failure of the balance spring in such a press the head is likely to descend suddenly, which might cause injury to the operator. My safety device comprises in general a latch connected with the operating mechanism for the toggle, this latch normally lying in a position to intercept a coacting latch member on the press frame if the toggles should move toward straightened position due to failure of the balance spring. Means is provided, acting automatically upon application of power to the power means for

operating the press, which serves to move the latch to inoperative position, providing the balance spring and other working parts of the press are in proper condition. However, if the balance spring has failed, the latching mechanism cannot be moved to inoperative position by this automatic means until the damage has been repaired.

I have chosen to illustrate my invention as applied to a press similar to that illustrated, described and claimed in the patent to Singiser, 2,006,751, granted July 2, 1935. Reference may be had to the said patent for a complete description thereof, and only sufficient description will be given here to permit an understanding of the operation of my improved safety device. The press illustrated in Fig. 1 comprises a frame 10 supporting a pressing bed 11 and a head lever 12 pivoted to the frame at 13. A pressing head 14 is mounted on the forward end of the head lever, and between the rear end of the head lever and the frame is arranged a balance or retriever spring 15 adapted to normally hold the head in open position. The usual toggles 16 and 17, pivoted together at their knuckle 18, are provided, straightening of which moves the pressing head to closed position. Power means is provided for closing the press, that illustrated comprising a cylinder 19 provided with a suitable piston 20 and a piston rod 21 which is operatively connected to the toggles so that movement of the piston rearwardly, or to the left in Fig. 1, straightens the toggles and closes the press. Control of fluid pressure to cylinder 19 is effected through a piston valve 22 in valve chamber 23, the piston being normally biased in the position of Fig. 5 when the press is open. In this position it will be noted that the passage 24 leading from cylinder 19 communicates through exhaust valve opening 25 with muffler 26. The inlet of fluid pressure to valve chamber 23 is by means of inlet port 27 and conduit 27' under the control of operating handle 28 which may be a single member or preferably a two-hand control. Actuation of the operating handle opens a valve 29 or valves 29 admitting fluid pressure through conduit 30 from a suitable source. Upon pressure entering valve chamber 23 through port 27 piston valve 22 is moved to the left in Fig. 5, thus closing exhaust port 25 and uncovering the passageway between the inlet end of valve chamber 23 and the passageway 24 leading to cylinder 19. Thereupon piston 20 is moved rearwardly and means is provided for setting up a maintaining circuit when the pressing members

have reached closed position. This maintaining means comprises a cam bar 31 movable with the piston rod 21, there being a notch 32 in the cam bar into which follower 33 drops when the 5 pressing members reach closed position. This actuates bell crank 34 in counter-clockwise direction, causing the vertical arm 35 of the bell crank to contact the stem 36 of maintaining valve 37 and admitting fluid pressure from a 10 suitable source 38 by means of conduit 39 to a port 40 in the passageway 24 leading to cylinder 19. This establishes maintaining pressure against piston 20 and the operator may then release the handle 28 or the two-hand control, 15 whichever is used.

To open the press the operator depresses foot treadle 41 which through link 42 moves bell crank 43 clockwise so that arm 44 of the bell crank contacts stem 45 of piston valve 22 and 20 moves the valve to the right (Fig. 5), thus opening exhaust port 25, permitting evacuation of cylinder 19 to the atmosphere. Simultaneously with this action, a portion of arm 44 of bell crank 43 contacts a forwardly projecting cam 25 surface 46 of bell crank 34 which serves to move that bell crank in a clockwise direction, thus removing the pressure from valve stem 36 and permitting valve 37 to close, thus cutting off the supply of fluid pressure from source 38 to 30 cylinder 19. The spring 15 then returns the pressing head to open position.

My improved safety device comprises cooperating latch members, one of which is secured to the frame and the other connected with the 35 operating toggles and so arranged that the latch members coact to hold the pressing members in open position if the balance spring should fail. The embodiment disclosed comprises a latch member in the form of a bell crank 47 pivotally connected to downwardly extending lugs 48 on piston rod 21. One arm of this bell crank is formed in the shape of a hook 49, and a pin 50 is supported from the frame or power cylinder in 40 position to be engaged by the hook as the piston rod 21 moves rearwardly to straighten the toggles. The other arm 53 of the bell crank enters the hollow piston rod through a slot 53'. Normally the parts lie in the position shown in 45 Fig. 1 where it will be observed that bell crank 47 is free to move in a counterclockwise direction to raise hook 49 to a position where it will fail to engage pin 50. However, if balance spring 15 should fail, the parts would move to the position shown in Fig. 2, where the toggles have 50 straightened slightly, due to the failure of the balance spring, and hook 49 is firmly engaged with pin 50. This hook and pin connection is made sufficiently strong that application of 55 normal closing pressure to the parts in the position of Fig. 2 will result in no action whatever, the parts 49 and 50 being made sufficiently strong to withstand the action of the power means.

Means is provided for automatically moving the latch to inoperative position upon operation 60 of the power means. The embodiment illustrated comprises a fluid actuated movable abutment arranged to be supplied with fluid pressure simultaneously with the application of fluid pressure to the power cylinder. To this end I have 65 illustrated piston rod 21 as being of hollow form and provided at one end with a movable abutment or piston 51 connected with a plunger or rod 52 which is arranged for horizontal movement, in the course of which it will normally 70 contact the upwardly extending arm 53 of bell

crank 47, thus moving the bell crank in a counterclockwise direction and moving the hook 49 to inoperative position as shown in Fig. 3. The plunger 52 may be provided with a bearing 54 to maintain its alignment, there being a collar 55 limiting the movement of piston 51 and its associated rod in one direction and there being a shoulder 56 adapted to contact piston 51 and limit its movement in the other direction. A spring 57 normally biases piston 51 in its forward 10 or right-hand position, as seen in the drawing. The forward end of the hollow piston rod 21 communicates with the passage 24 whereby fluid pressure being supplied to power cylinder 19 will simultaneously enter the hollow piston rod and 15 move the piston or abutment 51 rearwardly or to the left as seen in the drawing. Spring 57 is not a very heavy spring, the result being that abutment 51 is moved to the limit of its movement almost instantaneously upon the application 20 of pressure to cylinder 19, so that its action takes place before piston 20 has made an appreciable movement. This preliminary movement of abutment 51 causes plunger 52 to move the hook 49 to inoperative position as shown in Fig. 3, providing all the working parts of the press are in proper condition. It will be apparent, however, that with the parts in the position of Fig. 2, consequent upon failure of balance spring 15, application of pressure to the abutment 51 can cause no movement of the plunger 52 as the hook 49 is firmly engaged about the pin 50. Therefore the press cannot be operated until the damaged parts have been repaired.

Means is provided for automatically returning the parts of the safety mechanism to the position of Fig. 1 upon opening of the press. If sufficient pressure remains in cylinder 19 until the press is fully open the hook 49 will be held in the position of Fig. 3 during such opening movement. If, however, pressure is suddenly relieved in cylinder 19 to the point enabling spring 57 to return abutment 51 to the right-hand end of its stroke, plunger 52 will move to the right and bell crank 47 will move clockwise until arm 53 reaches the right-hand end of slot 53'. In this position hook 49 is substantially horizontal and cam surface 58 on the back of the hook will cause the hook to be lifted until it has passed pin 50 on the return stroke.

It will thus be apparent that I have devised a very simple but effective safety mechanism for preventing accidental closing of the press head upon failure of the balance spring. The mechanism also prevents operation of the power means for operating the press during the continuance of such damaged condition. It will also be noted that the safety mechanism requires no attention from the operator so long as the parts of the press are in proper working condition and is released automatically each time that power is applied to the press. It will further be noted that the operating parts required are few in number and not likely to get out of order.

What I claim is:

1. In a press of the class described, the combination of coacting relatively movable pressing elements, power means for moving one of said elements to close the press, means independent of the power means for normally holding said element in open position, safety means automatically operable to hold said element in open position upon failure of the second-named means, said safety means being arranged normally to prevent the operation of said power 70 75

means, and means for moving said safety means to inoperative position, said last-named means being operable by the flow of power to said power means.

- 5 2. In a press of the class described, the combination of coacting relatively movable pressing elements, power means for moving one of said elements, means independent of said power means for normally holding said element in open 10 position, safety means automatically operable to hold said element in open position upon failure of the second-named means, said safety means being arranged normally to prevent effective operation of said power means, means for moving said safety means to inoperative position, and means for actuating said last-named means automatically by application of power to said power means.
- 15 3. In a press of the class described, the combination of coacting relatively movable pressing elements, fluid pressure actuated power means for moving said elements, means for normally holding said elements in open position, safety means automatically operable to hold said elements in open position upon failure of the second-named means, said safety means being arranged normally to prevent the operation of said power means, and a fluid motor for moving said safety means to inoperative position, said 20 motor being operable by application of fluid pressure to said power means.
- 25 4. In a press of the class described, the combination of coacting relatively movable pressing elements, means for closing said pressing elements including a cylinder, piston and hollow

25 piston rod, a member arranged normally to prevent movement of said piston rod in press-closing direction, a movable abutment in said hollow piston rod, a connection between said abutment and said member for moving the member to an inoperative position upon movement of the abutment, and said abutment being operable by fluid pressure admitted to said cylinder.

5 5. In a press of the class described, the combination of a frame, coacting relatively movable 10 pressing elements carried thereby, spring means for normally holding one of said elements in open position, means for moving said element to closed position, and safety means for latching said last-named means to the frame when the 15 press is open, said safety means comprising co-operating latch parts normally in unlatched position and movable to latched position by slight movement of said element toward closed position upon failure of said spring means.

20 6. In a press of the class described, coacting relatively moving pressing members, a cylinder and piston motor for moving one of said members in press-closing direction, spring means for normally holding said one member in press-open 25 position, latch means normally preventing press-closing movement of said motor, said latch means comprising latch parts normally in unlatched position, and movable to latched position upon slight press-closing movement of said 30 motor, a second fluid motor for moving said latch means to a position permitting press-closing movement of said power means, and one fluid supply means for both motors.

ALBERT MATTHEWS. 35
